UNITED STATES PATENT OFFICE.

WILLIAM O. RHODES, OF COVINGTON, KENTUCKY.

BUILDING MATERIAL.

Application filed March 5, 1924. Serial No. 697,117.

To all whom it may concern:

Be it known that I, WILLIAM O. RHODES, citizen of the United States, residing at Covington, in the county of Kenton and State of Kentucky, have invented certain new and useful Improvements in Building Materials, of which the following is a specification.

The present invention relates to a building unit and more particularly to a combination fire proof lath and wall structure designed for the construction of dwelling, business, and amusement houses, garages, and every kind of buildings where laths and plaster are used, both for exterior and interior use. This structure being made completely of metal is entirely fire proof and rigid and channel irons are used to give the sufficient weight and strength to the structure in order to carry the necessary load as may be required. The parts are constructed in uniform sizes and can therefore be economically manufactured. The structure is designed for receiving plaster on the interior and stucco on the exterior and eliminates the use of wooden studding except around openings where casings are to be nailed.

An important object of the invention is to provide a unit of this nature possessing an efficient and simple construction which may be readily and quickly assembled with other similar units and which will be durable, reliable, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a plan view of one unit embodying my invention,

Figure 2 is an end view thereof,

Figure 3 is a transverse section taken substantially on the line 3-3 of Figure 1,

Figure 4 is an enlarged detail section taken substantially on the line 4-4 of Figure 1,

Figure 5 is a top plan view of a plurality of the units assembled,

Figure 6 is a detail horizontal section showing how the units are fastened together,

Figure 7 is an end elevation of a modified form of the unit,

Figure 8 is an enlarged detail section showing the manner in which the modified form of the units are fastened together, and Figure 9 is a detail perspective showing a section taken substantially on line 9-9 of Figure 1.

Referring to the drawing in detail and particularly the structure disclosed in Figures 1 to 6 inclusive it will be seen that the unit here disclosed includes a sheet of metallic material indicated by the letter A. This sheet 2 is bent along its transverse center line so as to provide a V-shaped sectional formation indicated at 5 and provided intermediate its ends with a slot 6. Right angularly extending flanges 7 provided on the transverse ends of the sheet A and on their edges are provided with intermediately disposed tongues 8 substantially the same length as the slot 6.

The sheet A is provided with a plurality of series of projections B which are formed by the incisions 9. The projections are provided on both the faces of the sheet so that plaster or stucco may be readily engaged therewith as will be understood by those skilled in the art.

In Figure 5 I have shown one way in which the units may be assembled so as to form an outer wall and an inner wall spaced from each other. The flanges 7 of adjacent units are in abutment with each other and riveted or bolted together as at 10 with channel irons 11 so as to give the structure the necessary strength for supporting the weight of a roof or the like as well as the weight of the units themselves. The front wall C as illustrated in Figure 5 comprises a plurality of the units A and the flanges 7 thereof are received in the pockets formed by the V-shaped sectional formation 5 and the tongues 8 (see Figure 6) project through the slot 6 of the section or units A of the rear wall D and are then bent over upon the V-shaped sectional formation 5 thus securely locking the front and rear walls together. In forming the corner the flanges 7 of the two inner wall units A are receivable in the corner unit A' of the outer wall C. This unit A' is the same as unit A except that it is bent intermediate its ends at right angles along the center line of the V-shaped sectional formation 5 and the tongues of the inner wall unit will pass through the slot thereof and bend as previously specified.

The units shown in Figures 7 and 8 and

indicated generally by the letter E are the same as units A except that they are not provided with the V-shaped sectional formation 5 and the flanges 7. The ends of these units E are provided with hook shaped flanges 15 extending in opposite directions as is clearly illustrated in Figure 7 so that adjacent flanges may be engageable with each other as shown in Figure 8 so that a bolt 16 may be passed therethrough. It is also preferable to place the channel iron 17 so as to be held in place by this bolt 16 thereby strengthening the assembled structure. This modified form is used where only one wall is to be provided in distinction to the two walled structure shown in Figure 5.

Referring particularly to the disclosure shown in Figure 1 in conjunction with Figures 2 and 7 attention is called to the manner in which the projections B are formed. The slits 9 are V-shaped and the V-shaped straps formed thereby are alternately bent in and out with respect to the sheet thus forming projections B so that the intermediate portion of each projection is higher than the extremities thereof so that plaster or stucco may be efficiently pressed into engagement therewith. It will be seen that the plaster and stucco may be pressed through the openings which will be formed so as to engage both the front and rear projections and thus the plaster and stucco will be more efficiently engaged with the unit than with an ordinary unit of laths.

It is evident that the units E could be used for the construction of columns by being bent circular so that its flanges 15 engage each other thereby forming a cylinder. By the use of ordinary mechanical skill there is hardly any building structure wherein plaster and stucco are useful in which my units may not be utilized to advantage. These units may be made of any desired weight or gage of sheet iron and may be either galvanized or painted and of course may be made in desired widths and lengths. When the load to be carried is not great, the rivets or bolts 10 and the channel irons 11 and the bolts 16 and channel irons 17 may be eliminated.

It is thought that the construction and use of these units have now been sufficiently described and illustrated for the purpose of disclosing the invention. If it is desired, however, that numerous changes in the details of construction, and in the combination and arrangement of parts may be resorted to without departing from the spirit or scope of the invention as hereinafter claimed or sacrificing any of its advantages.

Having thus described my invention, what I claim as new is:

1. A building unit of the class described including a sheet body bent intermediate its ends so as to provide a V-shaped sec-

tional formation having an intermediately disposed slot, flanges extending from the ends of the sheet and provided at their edges with the tongues receivable in slots of other similar units all in the manner and for the purpose specified. 70

2. A building unit of the class described including a sheet body bent intermediate its ends so as to provide a V-shaped sectional formation having an intermediately disposed slot, flanges extending from the ends of the sheet and provided at their edges with the tongues receivable in slots of other similar units, the sheet body of the units being provided with a plurality 75 of V-shaped slits arranged in a plurality of series so as to form straps, said straps being bent so as to project alternately from opposite faces of the sheet body. 80

3. A structure of the class described formed from a plurality of assembled units each including a sheet body having end flanges and an intermediately disposed V-shaped sectional formation having a slot 90 therein, tongues projecting from the flanges for being received in the slots of other units and bent over upon the V-shaped sectional formation. 95

4. A structure of the class described formed from a plurality of assembled units each including a sheet body having end flanges and an intermediately disposed V-shaped sectional formation having a slot 100 therein, tongues projecting from the flanges for being received in the slots of other units and bent over upon the V-shaped sectional formation, the flanges of the units being disposed adjacent each other and channel irons extended longitudinally therewith and fixed thereto for bracing the structure so 105 that it may hold the required load. 110

5. A building structure of the class described including a front wall and a rear wall, each wall formed of a plurality of units, each unit consisting of a sheet body 115 having end flanges provided with tongues on their edges, the body provided with an intermediately disposed V-shaped sectional formation with a slot therein, the tongue of adjacent sections of one wall being disposed in abutment with each other so as to lie alongside of each other, means for fixing the last mentioned flanges together, and the tongues of the flanges piercing the slots of the adjacent unit of the other wall 120 and bent over upon the last mentioned unit all in the manner and for the purpose specified. 115

In testimony whereof I affix my signature in the presence of two witnesses.

WILLIAM O. RHODES.
